DOOR CONTROL APPARATUS

Chase Blum, Cincinnati, Ohio

Application December 1, 1944, Serial No. 566,127

2 Claims. (Cl. 268—72)

1

This invention relates to apparatus for controlling doors which are comparatively difficult to open, for one reason or another.

An object of the invention is to provide a simple but effective means for facilitating the opening of a door, from the inside or outside, without resort to complicated or elaborate working elements.

Another object is to provide for the multiplication of forces in the operation of such an apparatus, to the end that any door, however tight-fitting or frozen, will readily yield and open upon application of ordinary force to the actuating lever of the apparatus.

Another object is to provide a durable and reliable device of the character stated, which readily may be fitted to doors and frames having various offset relationships, as well as flush fitted doors and frames, without increasing the effort incident to installation.

The foregoing and other objects are attained by the means described herein, and illustrated in the accompanying drawing, in which:

Fig. 1 is a fragmental elevational view showing the apparatus of the invention installed upon a door and frame.

Fig. 2 is a perspective view showing the relative positions of parts when installed upon a door and frame.

Fig. 3 is a detail perspective view of a striker element, such as may be used in effecting an installation involving a considerable offset between the door and the frame.

Doors of one kind or another may be difficult to open for various reasons, among which are the tendency of some doors to sag, warp, or stick to the frame due to other factors. Perfectly fitted doors also may be difficult to open, if the initial opening effort is required to break a frost seal, or a vacuum seal, as may sometimes be encountered in closures for refrigerators, cooling rooms, or the like. Irrespective of the reason for the difficulty in opening the door, however, the apparatus about to be described herein will solve the problem and perform the opening operation with maximum effectiveness, and with a minimum of expenditure of time and effort.

In the drawing 4 indicates a door mounted upon a frame 5 by means of one or more hinges 6. The forward face of the door, which is the face shown on the drawing, may be assumed coplanar with, or offset forwardly of, the exposed face of frame 5.

In order that the door may be kept in a tightly closed condition, it may be equipped with a door closing device 7, the function of which is to apply a force to a bumper plate or element 8 of the door, as long as the door is in a closed or nearly closed position. Any required number of door

2

closing devices may be applied to a door such as 4. The door closing device may be of any suitable type, but for the purpose of this explanation there is illustrated the door closing device of C. Blum Patent No. 2,046,892, dated July 7, 1936. The device includes a roller 9 adapted to contact the bumper plate 8, and to be held against said plate by the action of springs contained within the barrels or cylinders 10. The aforesaid Patent No. 2,046,892 may be consulted for a detailed description of the door closing device 7.

The device for opening the door, may comprise a lever 12 pivoted as at 13 upon a bracket 14 screwed or otherwise fastened to the forward face of the door, the lever being movable about its pivotal mounting 13 in a plane normal or perpendicular to the plane of the door 4. The bracket 14 is mounted in close proximity with the edge 15 of the door.

20 Lever 12 has a handle end 16 and a contactor end 17, the latter being provided with an anti-friction means, for example, a roller 18 mounted upon a vertical axle 19. Between the pivot pin 13 and the contactor 18, the lever preferably is formed with a gooseneck configuration as indicated at 20, so that the contactor end portion thereof will advance toward the door frame substantially at right angles, when the door is swung toward the closed position. A wear plate or 25 striker element 21 may be applied to the frame of the door, if desired, to prevent roller 18 from injuring the frame. The striker element may be substantially flat as shown, provided that the door and the frame are substantially coplanar at their outer faces. In those instances where the outer face of the door is disposed materially forwardly or in advance of the plane of the door frame, the striker element may be modified as 30 illustrated at 22 of Fig. 3, to present a striking surface 23 sufficiently forward of the door frame, to make contact with roller 18 in the desired manner. It may be noted that the striking surface 23 can be located forwardly of the mounting flanges 24, to any extent necessary for accommodating doors offset to the frame at varying distances.

From the foregoing description, it should be apparent that an operator grasping the handle 16 and pulling forwardly in the direction in which 35 the door opens, will rock the lever 12 about its pivot 13 and thereby apply a very substantial force to the striker element 21, for initiating an opening movement of the door. As the gooseneck portion 20 of the lever is much shorter than the handle end beyond pivot 13, the force applied by the operator to handle 16 will be greatly multiplied in impinging upon the striker element 21. The force applied to the striker element, moreover, will be transmitted along an arc de-

scribed by the gooseneck portion of the lever, with the result that roller 18 promptly advances along the exposed face of the striker element 21, in the direction of the door edge 15. The resulting action closely simulates that of driving a wedge behind the door to initially break the seal and thereby facilitate full opening of the door. Movement of lever 12 in the clockwise direction of rotation about pivot 13, may be limited by reason of the lever abutting bracket 14 at point 10 25, or at any other convenient location. It is necessary that the movement of the lever be limited as stated in order to prevent inadvertent closing of the door with the contactor end 17 in position to be wedged at the door jamb.

Means may be provided for manipulating the door opening lever from the inside of the door. Said means may comprise a reciprocable shaft 26 extending through a hole formed in the door at right angles to the plane thereof. The shaft may be supported at the inner and outer faces of the door, by means of metallic plates or discs 27 and 28 bored to slidably receive the shaft. Plate 27 is the exterior plate, and may be mounted upon the door in any suitable manner, as by means of screws or other fasteners 29. In a similar manner, plate 28 may be fixed to the inner face of the door.

The shaft at its outer end, may be provided with a head 30 located directly behind the lever 12 at a short distance from handle 16. By means of a knob or the like 31 applied to the inner end of shaft 26 at the location 32, the shaft may be reciprocated to cause the head 30 to move the lever in clockwise direction about its pivot 13, for initially wedging the door from its closed position. The shaft 26 may be provided with a stop 33, which may conveniently be in the form of a nut threaded onto the shaft, said stop being provided for the purpose of limiting the outward movement of the shaft.

Between the head 30 and the adjacent flange or bearing member 27, a comparatively light spring 34 may be interposed, this being for the purpose of yieldingly urging the handle end of the lever outwardly or away from the door, so as to maintain the roller 18 normally in contact with the striker plate element 21 while the door is closed. This spring 34, of course, lacks the force to manipulate the lever to the door opening position, except with the aid of force applied manually to the knob 31 for moving shaft 26 toward the lever. From the foregoing, it will be understood that shaft 26 will be advanced forwardly by the action of spring 34 when the door opener is actuated by means of handle 16. When said lever is actuated from inside the door, shaft 26 is advanced by means of force applied to knob 31 in the direction of the shaft head 30.

The device herein disclosed is applicable to practically any door, or may be rendered applicable by associating it with a striker element properly extended to compensate for the offset between the frame and the outer face of the door. In the application of the device to refrigerators or cooling compartments, for example, the control means for the door consisting of the door opening device and one or more door closers such as 7, results in a normally tight closure preventing leakage through the jamb and thereby effecting a saving of power or refrigerant. A door controlled in accordance with the present invention prevents day and night loss or waste, in the maintenance of desired temperatures within a refrigerator or cooler. The door may be opened as

effectively from the interior of the cooler or refrigerator as from the exterior thereof.

What is claimed is:

1. A door opener comprising in combination, 5 a lever having a handle end and a contact end, and means for pivoting said lever on the door for rocking movement in a plane normal to the door, with the contact end thereof projecting beyond an edge of the door to overlie the door frame, the pivot means being so located upon the lever as to advance the contact end toward the door frame, upon displacement of the handle end away from the plane of the door, a striker element on the door frame, and anti-friction means 15 on the contact end of the lever, in constant engagement with the striker element while the door is closed, a shaft extending through the door for displacing the handle of the lever, and a spring associated therewith to yieldingly maintain said 20 constant engagement between one end of the shaft and the handle end of the lever, a hand grasp on the opposite end of the shaft for manually reciprocating the shaft, and adjustable stop means on the shaft between the hand grasp and 25 the spring for limiting reciprocation of the shaft in the direction of displacement of the handle to the door opening position.

2. The combination of a door and a door frame, 30 a door opener comprising a lever having a handle end, and an opposite end of gooseneck formation, means pivoting said lever upon the door adjacent to the gooseneck portion of the lever, said pivoting means being upright so as to support the lever for rocking movement in a plane perpendicular to the door, with the gooseneck portion projecting beyond an edge of the door to overlie the door frame, a striker element on the frame, a terminal end on the gooseneck portion of the lever directed substantially perpendicularly to the 35 striker element, a roller on the terminal end of the lever, a shaft extending through the door for reciprocation transversely of the plane of the door, said shaft having a head on one end thereof to contact the lever, a pair of apertured plates applied one to the outside surface of the door, and the other to the inside surface thereof, with the shaft extending through the apertures of the plates, a hand grasp on one end of the shaft interiorly of the door, adjustable stop means on the shaft between the hand grasp and the interior plate of the door, for limiting reciprocation of the shaft in the direction of displacement of the handle to the door opening position, and yielding means applied to the shaft for maintaining a contacting relationship between the shaft and the handle end of the lever.
